UNITED STATES PATENT OFFICE.

THOMAS H. RAY, OF DORCHESTER, MASSACHUSETTS.

ICE-MAKING MACHINE.

1,077,916.

Specification of Letters Patent.

Patented Nov. 4, 1913.

Application filed March 20, 1913. Serial No. 755,653.

To all whom it may concern:

Be it known that I, THOMAS H. RAY, a citizen of the United States, residing at Dorchester, in the county of Suffolk and 5 State of Massachusetts, have invented certain new and useful Improvements in Ice-Making Machines, of which the following is a specification, reference being had therein to the accompanying drawings.

10 The object of my invention is to provide an ice making machine wherein substantially all of the heat absorbing surfaces, including the feed and the return header heretofore located above the water in the 15 tank, may be submerged in the water, and utilized as ice forming surfaces; and I attain this object by means of a thin hollow metallic plate both ends of which are provided with metal headers with suitable 20 openings communicating with the interior of the hollow plate; *i. e.* a lower blade feed header at the bottom, and an upper blade return header at the top, of the plate. By this structure I also can easily drain or blow off 25 any oil or sediment that may collect at the bottom of the interior of the freezing blades. Further, this structure permits the substitution of welded joints, for all prior metal connections, made within or over the water 30 in the freezing tank, and also the doing away with the assemblage of a great number of parts. Still further, this structure permits of a greater or less duplication of hollow plates to increase the area of ice 35 forming surfaces. Also the contraction and expansion of the parts may take place without injury to them.

By providing openings of suitable size between the lower feed blade header and the 40 lower portion of the hollow plate, the lower feed blade header serves as a reservoir from which liquid refrigerant will flow equally into the hollow plate or plates, while the area of the openings leading from the upper portion 45 of the plate into the upper return blade header is enough larger than that of those in the lower blade, to permit the free escape of the liquid or gas employed in freezing, or the hot gas used in melting the ice off 50 of the freezing surfaces of the plate, and blade headers.

In the drawings illustrating the principle of my invention and the best mode now known of embodying the same in operative 55 structure, Figure 1 is a perspective view showing my invention; Fig. 2 shows it in

elevation, mounted in a water tank; Fig. 3 is a bottom plan of the return blade header, one element of my structure; Fig. 4 illustrates in plan, the bottom feed blade header, another element; Fig. 5 is a longitudinal sectional view of my structure; Fig. 6 is an end view of it, while Fig. 7 shows it in cross section. Fig. 8 is an end view of the water tank, one end of the tank having 60 been removed for the purpose of clearly showing the pipe connections, water line in the tank, and ice on the ice forming surfaces. Fig. 9 shows in plan, the tank with connecting piping, a portion of the tank 65 being broken out to reduce the size of the drawing. Fig. 10 is a cross sectional view showing ice forming surfaces immersed in water, with ice thereon; flooring, hot gas pipes underneath it and resting on the bottom of the tank. Fig. 11 shows, in perspective, my invention when only one freezing blade is used, in combination with a top 70 blade header and a bottom blade header. Fig. 12 is a longitudinal section of what appears in Fig. 11. Fig. 13 is a perspective view of one feature of my invention, namely, a blade header; that shown being a return blade header, which is substantially the same as a feeding blade header. 75

In a suitable water tank A, Figs. 2, 8 and 9, is mounted one or more ice forming devices embodying my invention clearly shown in perspective in Figs. 1 and 11. A bottom feed blade header 1 and a top return blade 80 header 2 are formed out of two lengths of pipe; a portion of each being compressed so that its opposite sides are substantially parallel, see Figs. 3, 4 and 7, the vertical parallel sides 3, 3, 4, 4, being designed to 85 serve as ice forming surfaces. Lying between the top and the bottom header is a hollow blade 5 of thin steel, Figs. 5, 7, and 11, being in cross section, a narrow parallelogram, the width of which is substantially 90 the equal of the distance between the parallel sides 3, 3, and 4, 4, of the bottom and top blade headers 1, 2. Holes 6, 7, Figs. 4, 5, and 12, suitable in size and number are 95 formed respectively in the top and the bottom blade header, to communicate with the hollow blade 5 when permanently fixed to the headers, as by acetylene welding. If desirable, duplicate blades as 5', 5'', etc. may be added, in like manner; the resulting 100 structure always being unitary, however, and embodying my invention. One or more 105

of these units, as appears in Figs. 8 and 9, may be used in a freezing tank, but in any event each of the units is intended to be entirely submerged in the water; both the top blade header and the bottom blade header passing through the walls of the tank below the water line of the tank and provided with suitable stuffing boxes, not shown.

10 Upon the bottom 8 of the tank, between each unit, are hot gas coils 9 covered with boarding 10 constituting the floor of the tank, upon parts of which each unit rests. A cover B, rests upon the top side of the tank, 15 and wooden timbers C which also serve to secure the top of the units.

To supply to each unit a refrigerant, there are provided the usual and well known connections. For example, anhydrous ammonia 20 being used as a refrigerant, there leads from a liquid header D, Figs. 2, 8 and 9, outside of the tank, a liquid feed pipe E with a valve F therein, which pipe is connected to the open end of the bottom blade header 25 1; while a return pipe G with a valve H, leads away from the open end of the top return blade header 2.

For the purpose of harvesting the ice, hot 30 gas may be properly introduced into each bottom blade header 1 from a hot gas header I outside of the tank and having a gas feed pipe J with a valve K opening into the liquid feed pipe E, ahead of its valve F. To melt any ice that may freeze to the 35 floor 10, Figs. 2, 8, 9, 10, of the tank, a hot gas releasing pipe L leads from the hot gas header I to one end of each hot gas coil 9 below the floor; the other end of each coil, being in turn connected by a pipe M with 40 valve N to a hot gas return header O, also outside of the tank.

To use my invention, water fills the tank to a point to cover the ice forming unit. Liquid ammonia, from the liquid header D 45 passes to each bottom blade in the tank; the hot gas valves J, N, being closed. The liquid ammonia fills the bottom feed blade header 1, and under a reduced pressure passes up through the holes 7 into the blades 5, where it boils and becomes equally distributed through the blade, and then continues through the holes 6 in the top blade header 2, into the latter, and on through the return pipe G and its valve H into the 55 turn header P. It will now be obvious, that the refrigerant ammonia, freely enters the bottom feed blade header 1 at the bottom of the tank, is permitted, as it naturally tends to do, to rise, become evenly distributed 60 throughout the blades 5 and the top return blade header 2, and to do most efficient refrigeration; all of the ice forming surfaces of the blades 5, and the blade headers 1 and 2, being separated from the 65 refrigerant liquid by metal of equal thick-

ness, and also being surfaces lying in desirable parallel planes.

When sufficient ice, as in Figs. 8 and 10, has been formed on the unit, the liquid return valve H and the feed valve F, Figs. 70 8 and 9, controlling the flow of ammonia through the unit, are closed, and the ice allowed to "temper". The hot gas valve K to the unit, is slightly opened, the hot gas entering the bottom feed blade header 1 75 and filling the unit; next the return valve H being sufficiently opened, the hot gas becomes evenly and quickly distributed over the interior of all the equally thin ice forming surfaces of the blades and blade headers, 80 and almost simultaneously melts the skin of ice attached to the ice forming surfaces. At the same time, to sever the ice from the floor 10, Figs. 2, 8 and 10, of the tank, hot gas from the hot gas header I, is permitted to 85 flow from the hot gas header through the hot gas releasing pipes L, by opening the hot gas valves L' therein and also the valves N in the hot gas return pipes M. After this skin of ice is melted, the valves L', N, controlling the flow of hot gas for this purpose, 90 are closed. The resulting ice is thus freed, and, rising, floats upon the water ready to be lifted out by suitable apparatus.

It is to be understood that other refrigerants than ammonia may be used, say brine; and that the structure may be varied without departing from the principle of my invention.

Desiring to protect my invention in the 100 broadest manner legally possible, what I claim is:—

1. As an article of manufacture employed in making artificial ice, a blade header comprising a thin metallic pipe having two of 105 its sides opposite and parallel for the formation of ice thereon, and a third side lying between the said parallel ice forming sides and having passages therethrough for a refrigerant liquid, and being adapted to be 110 secured to, and coöperate with, a hollow metallic freezing blade.

2. In a refrigerating machine, a single, thin, hollow, metallic freezing blade; a single, thin, hollow, metallic freezing blade 115 header, across the top of the said hollow metallic freezing blade, for withdrawing the refrigerant liquid employed from the top portion of the hollow metallic freezing blade; a single, thin, hollow, metallic freezing blade header, across the bottom of the said hollow metallic freezing blade, for feeding the refrigerant liquid upward from the bottom of the metallic freezing blade; all of the exposed surfaces of said blade and header, being designed to be entirely submerged and utilized as heat absorbing surfaces for making ice.

3. In a refrigerating machine a series of two or more separate hollow metallic freez- 120

ing blades adapted to be entirely submerged in a water tank; means, whose surfaces are ice forming surfaces, designed to be below the surface of the water and connected with 5 the top portion of each of the hollow metallic blades, for withdrawing the refrigerant liquid employed from the top portion of the blades, simultaneously; and means, whose surfaces are ice forming surfaces, across the 10 bottom portions of the hollow metallic freezing blades, and below the level of the water, for simultaneously feeding the refrigerant

liquid upward from the bottom of the hollow metallic freezing blade; all designed to utilize for making ice substantially all of 15 the heat absorbing surfaces of the machine, within the walls of the water tank.

In testimony whereof I affix my signature in presence of two witnesses.
